UNITED STATES PATENT OFFICE.

JOHN FORSTER, OF LOS ANGELES, CALIFORNIA.

PENCIL ATTACHMENT.

1,153,211.

Specification of Letters Patent. Patented Sept. 14, 1915.

Application filed November 18, 1914. Serial No. 872,739.

To all whom it may concern:

Be it known that I, JOHN FORSTER, a citizen of the United States, residing at Los Angeles, in the county of Los Angeles, State 5 of California, have invented new and useful Improvements in Pencil Attachments, of which the following is a specification.

This invention relates to a pencil attachment.

10 It is the object of this invention to provide an attachment for lead pencils embodying a metallic stylus or marking point which may be utilized in lieu of the lead point of the pencil when it is desired to mark the surface of the material being worked with a greater degree of accuracy than is obtainable with the lead point.

Another object is to provide an attachment of the above character in which the 20 stylus point may be folded into an inoperative position when the pencil is in use and it is not desired to employ the metallic stylus.

Another object is to provide a foldable stylus carrying attachment for lead pencils 25 which may be readily applied to or removed from the lead pencil and which will serve as a pocket engaging clip when the stylus is in its inoperative position.

The invention is illustrated in the accompanying drawing, in which:

Figure 1 is a view in side elevation of the lead pencil showing the invention as applied, and with the stylus in its folded position. Fig. 2 is a similar view showing the 35 opposite side of the lead pencil with the attachment thereon. Fig. 3 is an edge view as seen in the direction indicated by the arrow 3 in Fig. 2. Fig. 4 is a detail horizontal section and elevation as seen on the line 40 4-4 of Fig. 2 in the direction indicated by the arrow. Fig. 5 is a view in elevation of the lower portion of the lead pencil showing the attachment with the stylus point disposed in its operative position.

45 More specifically, 6 indicates the body portion of the device which is tubular in form and adapted to receive the end of a lead pencil 7. The tubular member 6 is formed of metal and is divided longitudinally on one side thereof as indicated at 8 in Figs. 3 and 4 so as to render the body member 6 of a resilient character and permit its being expanded in inserting the pencil 7 therein; the side portions of the sleeve members 6 forming spring clips adapted to frictionally engage the pencil 7.

Encompassing one end of the sleeve member 6 is a yoke 9, the opposite arms of which are secured to the sleeve members 6 by a pivot pin 10 which extends across the interior of the sleeve 6 and forms a stop for limiting the inward movement of the sleeve on the end of the pencil 7. One of the arms of the yoke 9 is formed with a transversely extending convergent portion 11 terminating 60 in a stylus point 12 which normally projects in the direction of the length of the sleeve 6 and pencil 7.

The yoke 9 is adapted to be turned on its pivot pin 10 to position the portion 11 and 70 stylus point 12 so that they will extend along the sleeve member 6 as shown in Fig. 1; the stylus point 12 being then folded into an inoperative position. The outer ends of the arm portions of the yoke 9 are curved 75 at 13 and 14 to extend over the edge of the sleeve member 6 into engagement with the latter as shown in Fig. 4, when the stylus point 12 extends in either direction longitudinally of the member 6; the bent portions 80 13 and 14 forming tongues which coöperate with the connection portion 15 of the yoke 9 in engaging the opposite sides of the sleeve member 6 to normally hold the yoke 85 against too free rotation.

The connecting portion 15 of the yoke 9 serves to limit the pivotal movement of the yoke 9 in either direction; the connecting portion 15 abutting against the sides of the sleeve member 6 when the stylus is disposed 90 in either its open or closed position.

In the application and operation of the invention, the sleeve member 6 is placed on the lead pencil 7 adjacent the end of the latter with the stylus point 12 extending 95 alongside of the sleeve member 6 when it is not in use. When it is desired to use the stylus 12 the yoke 9 is rocked to position the stylus with its point projecting beyond the end of the pencil as shown in Fig. 5 whereupon the stylus may be drawn across the surface to be marked in the direction indicated by the arrow —a—. The connecting portion 15 of the yoke in abutting against the edge of the sleeve member 6 will serve 100 to prevent rotation of the yoke in the direction of the pressure imposed on the stylus 12.

The tongues 13 and 14 will coöperate with the connecting portion 15 of the yoke to hold the latter against free rotation; the 110 tongues 13 and 14 riding out of engagement with the edge of the sleeve member 6 on

pressure being applied to the member 14 when it is desired to restore the stylus to its normal folded position. When the stylus is disposed in its folded position alongside 5 of the sleeve member 6 it may be employed as a clip for engaging the edge of a pocket.

What I claim is:

A pencil attachment, comprising a split resilient sleeve adapted to receive a pencil, 10 a spring yoke embracing said sleeve and carrying a stylus point, said yoke having arms bent toward each other, a pin passing

through said yoke and said sleeve pivotally securing the yoke to the sleeve for extension of said stylus longitudinally of the sleeve in 15 either direction and for limiting the movement of the stylus in either direction.

In witness that I claim the foregoing I have hereunto subscribed my name this 29th day of October, 1914.

JOHN FORSTER.
